ELECTRON DISCHARGE TUBE

Hans Schedel, Stuttgart, Germany, assignor, by
mesne assignments, to Erich F. Huth G. m.
b. H., Berlin, Germany, a company.

Application August 25, 1937; Serial No. 160,771
In Germany August 26, 1936

5 Claims. (Cl. 250—27.5)

The invention relates to discharge tubes and the method of manufacturing them, said tubes having an envelope or composed of a metal bulb and a cover. More particularly the invention is concerned with the manner of uniting these two by a seal so as to insure vacuum tightness.

This seal, e. g., of glass, must be heated in order to insure tight adherence to the metal bulb. Heating the entire metal bulb however endangers the electrode system. The invention therefore provides for heating only that part of the bulb to which the seal must stick, and it attains this object by supplying the necessary heat by the seal itself. For this purpose the seal is poured onto the cover and said bulb part, thus being applied thereto in a state in which it contains the heat necessary for the seal to unite with this bulb part. The portion of the envelope to which the seal is applied is preferably a flange integral with the envelope so as to enhance the effect of the seal applied thereto.

Examples of the latter kind are represented in Figs. 1 to 5 each of which is a sectional view illustrating one embodiment of the invention.

In all these examples the metal bulb 1 has a flange 2 and a thin-walled annular body 3 whose wall thickness is much smaller than that of the bulb 1. Body 3 is fastened to flange 2. 4 denotes a disc-shaped cover which preferably is of a ceramic material. 5 indicates a seal by which cover 4 and bulb 1 are interconnected in a manner to insure vacuum tightness.

In the arrangement according to Fig. 1 the body 3 is part of a ring shaped body 6 which is welded to flange 2 with the assistance of a hard solder ring 7. Body 3 and disc 4 form a cup to receive the seal 5. Disc 4 has a reduced part 4' by which it joins the body 3. Disc 4 and body 3 are flush with each other on the outside.

In the arrangement according to Fig. 2 the body 3a is T-shaped and is thin-walled like foil. Body 3a is welded directly to flange 2 and at its inner edge extends over an annular recess 9 of the bulb 1 and abuts the disc 4 with which it is flush on the outside.

In the arrangement represented in Fig. 3 the body 3b is as in the arrangement shown in Fig. 1 a metal such as nickel, iron or an iron-nickel-cobalt alloy and forms part of an annular body 6 whose cross-sectional configuration is approximately like the one illustrated in Fig. 1. Disc 4 is of lead glass and has an annular groove 10 in its edge portion. Body 6 is provided with an annular recess 11. The reduced parts 4', 6' thus formed are flush with one another. The

body 1 is of pure iron, and the flange an iron-nickel-cobalt alloy.

The body 3c of the arrangement represented in Fig. 4 is a flat foil-like ring, arranged to cover annular grooves 12 of the flange 2.

A flat ring 3d of a metal such as nickel, iron or an iron-nickel-cobalt alloy having a foil-like thickness is shown also in Fig. 5. Flange 2 is so recessed by annular grooves 12 that between these there are annular edges supporting the rings 3d. Ring 3d is upturned at its outer edge and is at this edge supported by flange 2.

The seal 5 should be preferably such as to soften between 100 and 900° Celsius. It may be of glass, such as a glass containing lead, or the like and may also be composed of other materials of like nature. Also metals may be employed for forming the seal.

The bodies, 3a, 3d are preferably made of a metal, such for instance as an iron alloy, iron-nickel or iron-nickel-cobalt, or may consist of copper, tungsten or molybdenum, but may be made of other materials adapted to unite with the seal 5.

The bodies, 3a, 3d may be fastened to flange 2 by welding, soldering, rolling, or pressing. The rolling or pressing may be effected in the same operation in which bulb 1 is produced.

If the cover 4 is of a ceramic material it may be glazed before being fitted to the bulb 1.

The seal 5 is poured onto the parts 4, 3 in an easily fusible state and thus fills up all hollows or joints of the cup-shaped structure 4, 3. The seal may be applied thereto in a predetermined quantity. The bodies 3 are quickly heated by the hot seal 5 to temperatures at which they are able so to unite with the seal 5 that they will stick to each other. The rapid heating of the bodies 3 is due to the fact that they are thin-walled and is attributable also to the manner in which they are joined to flange 2, being so attached thereto that the smallest possible amount of heat shall be led away from them. This purpose is served by the parts 6 (Figs. 1 and 3) and the recesses 9 (Fig. 2), 11 (Fig. 3) and 12 (Figs. 4, 5) which provide a reduction of the cross section of parts which would carry away heat and thereby reduce the loss of heat during the sealing operation. In this respect recess 10 (Fig. 3) too is helpful.

Instead of covering the disc 4 entirely with the seal the arrangement may be such that only certain parts thereof shall be covered.

What is claimed is:

1. An electronic discharge tube having an open-ended metallic envelope, a metallic flange sur-

rounding the open end of the envelope, a ceramic closing disc within said open end and resting on the open end of said envelope, and a vitreous seal covering said disc and flange.

5 2. An electronic discharge tube having an open-ended metallic envelope, a thin walled metallic rim above said open end and having a relatively heavy body portion, means for securing said body portion to said envelope, a ceramic closing disc resting on the open end of said envelope, and a glass seal covering said disc and contacting with said rim.

10 3. An electronic discharge tube having an open-ended metallic envelope, a flange surrounding the open end of said envelope, a thin walled curved metallic rim having a relatively thicker basal portion, means for securing said basal por-

tion to said flange with open spaces between the two, a closing disc for the open end of said envelope surrounded by said flange and basal portion, and a continuous glass seal covering said disc and contacting with said rim.

15 4. The method of manufacturing electronic discharge tubes having a metallic envelope, comprising the following steps: applying a closure to the rim of the open end of the tube envelope, and pouring a glass seal over the outside surface of the closure and into contact with the rim of the envelope.

5. The method defined in claim 4 and in which the closure is heated before the glass seal is poured on it.

15 HANS SCHEDEL.
